UNITED STATES PATENT OFFICE.

NARCISSE N. S. DAUDELIN, OF FALL RIVER, MASSACHUSETTS.

AUTOMATIC THREAD-BOARD LIFTER FOR SPINNING-FRAMES.

SPECIFICATION forming part of Letters Patent No. 737,084, dated August 25, 1903.

Application filed September 17, 1902. Serial No. 123,675. (No model.)

To all whom it may concern:

Be it known that I, NARCISSE N. S. DAUDELIN, a citizen of the United States, residing at Fall River, in the county of Bristol and State of Massachusetts, have invented certain new and useful Improvements in Automatic Thread-Board Lifters for Spinning and Twisting Frames, of which the following is a specification.

This invention relates to spinning and twisting frames; and its object is to relieve the yarn from the strain which is caused by the short distance between the ring-traveler and the guide-wire on the thread-board when the ring-rail is at the highest point of the wind, the shortness of this distance causing the yarn to turn at a sharp angle where it passes through the guide-wire and ring-traveler. This trouble is aggravated when a large ring is used.

A further object of my invention is to insure better and stronger yarn by lessening the swing or ballooning of the yarn when the ring-rail is near the bottom of the wind.

I accomplish these results by making the thread-board vertically movable and providing means for automatically lifting it at the proper time, as hereinafter set forth, and particularly pointed out in the claims.

In the accompanying drawings, Figure 1 is a sectional end elevation of a ring-spinning frame embodying my invention. Fig. 2 is a similar view of one thread-board when raised. Fig. 3 is a front elevation of the upper part of a bobbin and adjacent parts. Fig. 4 is a perspective view of one of the rock-shaft bearings, and Figs. 5 and 6 show two views of the slide for said bearing.

The frame 1 supports on each side the vertical spindles 2, driven by bands 3 from the driving-drum 4. The ring-rails 5 are vertically movable to feed the thread to the bobbins 6. The thread is brought through the rolls 7, supported on top of the frame 1, and is led through a guide-eye 8 on the thread-board 9, attached to the frame 1 above the bobbins. The mechanism includes a heart-cam 10 on the shaft 11, from which motion is imparted to certain parts. All the foregoing elements are common to ring-spinning frames, and those skilled in the art need no

detailed description of them or their mode of operation.

My improvement lies in part in the thread-boards 9, which I render vertically movable, preferably by hinging them to the frame 1. Attached to each thread-board is an arm 12, and adjacent to each arm is an elbow-lever having two arms 13 and 14, the latter carrying a pin 15, bearing on said arm. The elbow-lever is fulcrumed in an adjustable bearing supported on a bar 16, fastened to the frame of the machine. The bearing is formed in a boss 17 at one end of a plate 18, having a longitudinal slot 19. The bar 16 also has a slot 20 at right angles to the slot 19. A slide 21 is interposed between the bar and the plate, consisting of a plate having a shallow groove 22 on one side to fit the bar 16, and a shallow groove 23 on the other side at right angles to the groove 22 and fitting the plate 18. The slide also has a central hole 24 for the clamping-bolt 25, which passes transversely through the bar, the slide, and the plate. This device enables the bearing for the elbow-lever to be adjusted both lengthwise and transversely of the bar 16. On one side of the machine the pin-carrying leg 14 of the elbow-lever is the upper, and on the other side of the machine it is the lower. The other legs 26 of the levers are connected by a rod 26, which is pivoted to them and is composed of two parts adjustable lengthwise by a slot 27 and clamping-bolt 28, so that the length of the rod can be altered as desired.

In order to operate all the elbow-levers simultaneously, a rock-shaft 29 runs through all the bosses 17 on one side of the machine, and all the elbow-levers are secured to said shaft by set-screws 30. The rock-shaft has at one end a rock-arm 31, connected by a longitudinally-adjustable rod 32 with one end of a lever 33, fulcrumed in a block 34, secured to the frame. At some suitable point on the lever is attached a wiper 35, preferably adjustable lengthwise by a slot and clamping-bolt and bearing on the periphery of the cam 10.

The operation of my invention is as follows: At every revolution of the cam the lever is lifted and lowered, and the rock-shaft is rocked alternately in opposite directions.

This causes the pins in the elbow-levers to depress all the arms 12, and thereby raise the thread-boards. This, as previously explained, lengthens the distance between the 5 ring-traveler 36 and the guide-eye 8 on the thread-board, and thus enlarges the angle of the thread at these points and relieves the strain. The raising of the thread-boards takes place simultaneously during the time the 10 ring-rail is traversing the upper part of its wind.

It will be seen that in machines where the thread-board is vertically adjustable on the frame my invention permits it to be set lower 15 than usual, so that in the case of a long traverse ballooning of the yarn is largely prevented and better and stronger yarn is the result.

What I claim as new, and desire to secure 20 by Letters Patent of the United States, is—

1. The combination with two hinged thread-boards each having an arm, of a rock-shaft adjustably supported adjacent to each arm, an elbow-lever on each shaft having a pin in

one leg bearing on said arm, a lengthwise-adjustable rod connecting the other legs of said elbow-levers, a rock-arm on one of said shafts, a lever, and an adjustable rod connecting said lever and said rock-arm. 25

2. In a ring spinning and twisting frame, 30 the combination with two hinged thread-boards each having an arm secured thereto, of stationary bars secured to the frame of the machine, bearings adjustably secured to said bars, rock-shafts journaled in said bearings, an elbow-lever on each shaft one leg of which engages with but is not attached to the arm on the adjacent thread-board, a lengthwise-adjustable rod connecting the other legs of said elbow-levers, a rock-arm on one of 35 40 said shafts, and means for actuating said rock-arm.

In witness whereof I have hereunto set my hand this 11th day of September, 1902.

NARCISSE N. S. DAUDELIN.
